(57) **CLAIM**

The ornamental design for an oral-care appliance (brush), as shown and described.

DESCRIPTION

FIG. 1 is a perspective view of an oral-care appliance (brush) showing the new design;

FIG. 2 is a left side view of the oral-care appliance (brush) of FIG. 1;

FIG. 3 is a front side view of the oral-care appliance (brush) of FIG. 1;

FIG. 4 is a right side view of the oral-care appliance (brush) of FIG. 1;

FIG. 5 is a back side view of the oral-care appliance (brush) of FIG. 1;

FIG. 6 is a bottom plan view of the oral-care appliance (brush) of FIG. 1; and,

FIG. 7 is a top plan view of the oral-care appliance (brush) of FIG. 1.

The broken lines shown on the head portion and the base of the neck are for illustrative purposes only and form no part of the claimed design.
